UNITED STATES PATENT OFFICE.

LOUIS FRED BOOKER, OF PHILADELPHIA, PENNSYLVANIA.

DESIGN FOR A RUBBER SCRAPING-KNIFE.

SPECIFICATION forming part of Design No. 30,404, dated March 28, 1899.

Application filed February 27, 1899. Serial No. 707,109. Term of patent 7 years.

To all whom it may concern:

Be it known that I, LOUIS FRED BOOKER, a citizen of the United States, residing at the city of Philadelphia, in the county of Philadelphia and State of Pennsylvania, have invented and produced a new and original Design for Rubber Scraping-Knives, of which the following is a specification, reference being had to the accompanying drawings, forming part thereof, in which—

Figure 1 is a side elevational view of a rubber scraping-knife, showing my new design; and Fig. 2 is a sectional view taken on the line $x-x$ of Fig. 1.

As illustrated in the drawings, the leading feature of my design consists in the configuration or shape of the rubber blade and handle comprising the scraping-knife for fine china, glassware, and the like. The rubber blade a is oval in form. The rear end a' of said blade is slightly curved, and the forward

end a^2 has a greater degree of curvature than the rear end. The lower edge a^3 of this blade is beveled, and the forward end a^2 is also beveled, as at a^4 . The blade a depends from a handle b , the rear portion b' of which is rounded and the forward portion clamp-shaped, as at b^2 , and beveled on both sides toward the surfaces or body of the blade a .

Having thus described my invention, what I claim as new, and desire to secure by Letters Patent, is—

The design for a rubber scraping-knife, substantially as shown and described.

In testimony whereof I have hereunto set my signature in the presence of two subscribing witnesses.

LOUIS FRED BOOKER.
